CLAIM

The ornamental design for a daybed, as shown and described.

DESCRIPTION

FIG. 1 is a top perspective view of a daybed showing our new design.

FIG. 2 is a front view of the daybed shown in FIG. 1.

FIG. 3 is a rear view of the daybed shown in FIG. 1.

FIG. 4 is a left side view of the daybed shown in FIG. 1.

FIG. 5 is a right side view of the daybed shown in FIG. 1.

FIG. 6 is a top view of the daybed shown in FIG. 1; and,

FIG. 7 is a bottom view of the daybed shown in FIG. 1.

The broken lines contained herein are show portions of the claimed design of indeterminate length.

1 Claim, 7 Drawing Sheets
